WIRE FABRIC AND METHOD OF MAKING
THE SAME

Otto Carl Scherfel, Haddon Heights, N. J., assignor to Audubon Wire Cloth Corporation, Philadelphia, Pa., a corporation of New Jersey

Application October 15, 1938, Serial No. 235,138

20 Claims. (Cl. 245—6)

My invention relates to wire fabrics constructed of helically coiled wires in interconnected or interengaged relation, and comprises improvements in that type of wire fabric in which a plurality of wires of the same twist are in nested relation.

My improved fabric is made up of a plurality of sets of helically coiled wires arranged in pairs with their ends permanently connected together, as by welding, and wherein the bights of the helices of the wires of the connected pairs are in alignment longitudinally of the fabric and are offset with respect to each other and/or adjacent helices transversely of the fabric; such helices being engaged by the bights of helices of the wires of other pairs arranged in the same relation. The helices of each of the respective wires are in such spaced relation as to receive between them the helices of wires of directly adjacent pairs and the result is the disposal of the helices of the several wires in very close relationship and in longitudinal alignment and offset with respect to adjacent helices transversely of the fabric.

A feature of my present invention is the close weaving of the several helically coiled wires, which are of the same twist; resulting in the production of a fabric with very smooth surfaces on both faces of the same.

These and other features of my invention are more fully set forth hereinafter; reference being had to the accompanying drawings, more or less diagrammatic in character, in which:

Figure 1 is a view of a unit pair of wires of the type employed in the construction of the fabric forming the subject of my present invention; such wires being shown in the connected relation of the completed fabric.

Fig. 2 is a plan view of a section or portion of completed fabric made up of unit pairs of wires of the type illustrated in Fig. 1; such view being partly broken away.

Figs. 2^A, 2^B and 2^C are diagrammatic views illustrating "sub-fabrics" which are developed in the formation of the wire fabric structure and which together comprise the complete fabric forming the subject of my invention.

Fig. 3 is an edge view of a portion of the completed fabric; looking in the direction of the arrow *a*, Fig. 2.

Fig. 4 is an edge view of a portion of the completed fabric; looking in the direction of the arrow *b*, Fig. 2.

Fig. 5 is a fragmentary sectional view, taken on the line V—V, Fig. 2, and

Fig. 6 is an edge view of a portion of the fabric

to illustrate the extreme flexibility of the same; such view indicating the curvature of the fabric when passing over a small pulley.

My improved fabric is in the nature of a triplex structure; that is to say, the helically coiled wires making up the same are in triple nested relation in a single thickness; such wires being of the same twist. The wires are arranged in paired relation and are subsequently connected together, but instead of having the bights of their helices in overlying parallel alignment lengthwise of the wires, I have arranged pairs of wires in offset relation with respect to each other with the bights of their helices in transverse alignment longitudinally of said wires and offset with respect to each other transversely of the same; each wire of each pair being interengaged by a wire of different adjacent pairs.

The helically coiled wires comprising my improved fabric are of the same twist and are assembled in pairs, with the respective wires of each pair in offset relation; such wires being subsequently connected together in such relation. The relation of the several wires composing the fabric is such that groups of singly-engaged wires produce what may be termed "sub-fabrics," three in number in the present instance; the several sets of wires making up the same being interconnected and so associated that their respective helices lie in nested relation and in close engagement throughout.

In Fig. 1 I have shown a pair of wires in the connected relation they present when embodied in the completed fabric. These wires lie in the same plane with their helices aligned transversely and in offset relation; the ends at the left side of the view extending downwardly and outwardly, while the ends at the right side of the view extend upwardly and outwardly.

In assembling pairs of these wires, the next pair will have an exactly opposite position to that of the pair illustrated in Fig. 1; just as though the pair of wires so illustrated was turned over so that at the left side, the ends would extend upwardly and outwardly, while at the right side the ends would extend downwardly and outwardly; a relation that is maintained throughout the extent of the fabric and is clearly illustrated in Fig. 2. In such relation, it will be observed that the helices of the second pair of wires—also in offset relation—nest between the helices of the first pair of wires; the helices of what may be termed the upper wire of the first pair, when considering the figure of drawing, lying in engagement with the helices of the lower or sec-

ond wire of the second pair. All of the assembled wires are in the same plane so that a single ply fabric results from the association of the several wires.

- 5 To clearly indicate the interconnected relation of the several wires, those making up the respective sub-fabrics are shaded—fabric A by horizontal lines; fabric B by vertical lines, and fabric C by cross-hatching. The respective sub-fabrics are clearly illustrated in the diagrammatic views, Figs. 2A, 2^B and 2^C, wherein they are shown independently in full lines, while the adjacent wires representing the other sub-fabrics are shown in broken lines.
- 15 Considering Fig. 2, which represents a fragmentary portion of a complete fabric, and the several diagrammatic views, it will be noted that the first pair of wires, indicated respectively at 10 and 11, and shown with their ends connected together, have their ends at the left of the several views extending downwardly and outwardly and connected at x, while the ends of the same wires at the right of the several views extend upwardly and outwardly, and are connected at x'.
- 25 The next pair of wires, indicated at 12 and 13, are arranged with their helices overlapping and/or nesting between the helices of the first pair, and are shown with their ends connected together; the ends at the left of the several views extending upwardly and outwardly and connected at y, while the ends of the same wires at the right of the several views extend downwardly and outwardly, and are connected at y'.
- 35 The next pair of wires, indicated at 10^a and 11^a, have their ends connected at x and x', and these connected ends lie in the same relation as the respective connected ends of the wires 10 and 11.
- 40 The next pair of wires, indicated at 12^a and 13^a, have their ends connected at y and y', and these connected ends lie in the same position as the respective connected ends of the wires 12 and 13.
- 45 The next pair of wires, indicated at 10^b and 11^b, are arranged in the same position and connected in the same manner as the wires 10 and 11, and the wires 10^a and 11^a.
- 50 The next pair of wires, indicated at 12^b and 13^b, are arranged in the same position and connected in the same manner as the wires 12 and 13, and the wires 12^a and 13^a.
- 55 The six groups of paired wires thus indicated, repeat in the same relation throughout the extent of the fabric.
- 60 It will be noted, however, that the wires of the respective pairs do not interengage with each other, nor with directly adjacent pairs of wires; in other words, following the arrangement of the several wires as above indicated, it will be noted that the wire 10, Figs. 2 and 2^A, interengages with the wire 13 of the second pair; that the wire 13 interengages with the wire 11^a of the third pair; that the wire 11^a interengages with the wire 12^b of the sixth pair, and that the wire 12^b interengages with the wire 10 of the seventh pair, and so on; the diagrammatic view, Fig. 2^A, showing the sub-fabric A which, for purposes of illustration only, is indicated as

starting with the wire of the first pair of wires, indicated in Fig. 2.

In like manner, sub-fabric B, illustrated in Figs. 2 and 2^B, is made up of wires 11, 12^a, 10^b, 13^b, and their repeats in the same order, and sub-fabric C, illustrated in Figs. 2 and 2^C, is made up of wires 12, 10^a, 13^a, 11^b, and their repeats in the same order.

The helices of the several connected pairs of wires are in such spaced relation as to receive 10 between them, in nested relation, the helices of wires or other pairs. Considering the wires 10 and 11, for example, illustrated at the upper portion of Fig. 2, it will be noted that their helices 15 present V-shaped spacing; the respective helices 10 of this pair of wires lying in contact with each other and in parallel relation, with their respective bights in transverse alignment but laterally offset. The bights of the wires 10, 10^a and 10^b, are indicated at c and c', of the respective wires; the bights of the wires 11, 11^a and 11^b, are indicated at d and d', of the respective wires; the bights of the wires 12, 12^a and 12^b, are indicated at e and e', of the respective wires, and the bights of the wires 13, 13^a and 13^b, are indicated at f and f', of the respective wires; the bights c', d', e' and f', being the lowermost bights of the respective wires, as illustrated in Fig. 2.

In the present arrangement, the spacing of 30 the helices of the respective wires is such that the helices (or parts of the helices) of four other wires, also in nested relation, may be accommodated between some part or all of the same. In this connection, particular attention is called 35 to the relation of the second pair of wires, indicated at 12 and 13, with respect to the first pair of wires, indicated at 10 and 11. The wires 12 and 13 have their bights arranged in a position opposite to that of the respective bights of 40 the wires 10 and 11. As illustrated in Fig. 2, the bights c' of the wires 10 are interconnected with the bights f of the wires 13, whose ends are connected to a wire 12. The wire 12 of this pair, however, is not connected with either wire of the 45 first pair of wires, indicated at 10 and 11, but with the wire 10^a of another pair directly adjacent to the first-mentioned pair of wires indicated at 10 and 11, and such arrangement continues throughout the extent of the fabric. 50

The wires of each connected pair are interconnected or separately hinged with the wires of adjacent pairs of the respective sets of wires, in the following manner:

Wires 10 engage wires 12^b on one side and wires 55 13 on the other; wires 11 engage wires 13^b on one side and wires 12^a on the other; wires 12 engage wires 11^b on one side and wires 10^a on the other; wires 13 engage wires 10 on one side and wires 11^a on the other; wires 10^a engage wires 12 on 60 one side and wires 13^a on the other; wires 11^a engage wires 13 on one side and wires 12^b on the other; wires 12^a engage wires 11 on one side and wires 10^b on the other; wires 13^a engage wires 10^a on one side and wires 11^b on the other; wires 10^b engage wires 12^a on one side and wires 13^b on the other; wires 11^b engage wires 13^a on one side and wires 12 on the other; wires 12^b engage wires 11^a on one side and wires 10 on the other; wires 13^b engage wires 10^b on one side and wires 11 on the other.

By disposing the several wires in this relation, the fabric presents no spaces between the respective helices, and the uniform spacing between the bights of the respective helices is very 75

slight; resulting in the production of a very closely woven structure.

The arrangement of the respective pairs of wires in the manner indicated presents the ends of the same with their connected helices in offset relation; that is to say, the connected ends of the wires 10 and 11; 10^a and 11^a, and 10^b and 11^b, at the left side of the fabric as indicated in Fig. 2, are inclined outwardly and downwardly and terminate adjacent to one face of the fabric, while the connected ends of the same wires at the right side of the fabric are inclined upwardly and outwardly, and terminate adjacent to the opposite face of the fabric. The connected ends of the wires 12 and 13; 12^a and 13^a, and 12^b and 13^b, occupy an exactly opposite position, as clearly illustrated in Fig. 2.

The rows of connected bights c and c' lie in one plane transversely of the fabric; the rows 20 of connected bights e and e' lie in one plane transversely of the fabric; the rows of connected bights d and f' lie in another plane transversely of the fabric, and the rows of connected bights f and c' lie in still another plane transversely of the fabric, and this relation is maintained throughout the entire extent of the fabric. The connected bights c and c' and d and f', are longitudinally aligned and alternate with the connected bights e and e' and f and c', also in 30 longitudinal alignment.

It will be clear from the foregoing description that the improved fabric forming the subject of my invention is made up of sub-fabrics—three in number—in which fabric A is composed of wires 10, 13, 11^a and 12^b, and their repeats; fabric B is made up of wires 11, 12^a, 10^b and 13^b, and their repeats, and fabric C is made up of wires 12, 10^a, 13^a and 11^b, and their repeats. By arranging the several sets of wires in connected 40 pairs in the manner indicated, offset with respect to each other, the three sub-fabrics—so to speak—are in interconnected relation without change of spacing and in a single ply or thickness. The spacing of the helices of the several interconnected wires is uniform throughout the entire extent of the fabric so that in the final condition a closely woven structure results with a substantially smooth and perfectly even surface on each side or face.

50 It will be understood, of course, that while I have disclosed and described a specific embodiment of my invention, I do not wish to be limited thereby and that various modifications may be made within the spirit and scope of my invention, all of which is believed to be included in the appended claims.

I claim:

1. A wire fabric composed of helically coiled wires arranged in pairs, with the spirals of the 60 wires of each pair in aligned relation and offset laterally with respect to each other; said wires having their ends permanently connected together and each wire of each connected pair being in interconnected relation with a wire of different adjacent connected pairs of wires.

2. A wire fabric composed of helically coiled wires having their ends connected together and arranged in unit pairs, with the spirals of the 70 wires of each pair in aligned relation and offset laterally with respect to each other; each wire of each connected pair being in interconnected relation with a wire of different adjacent unit pairs of wires.

3. A wire fabric composed of helically coiled 75 wires arranged in pairs, with the spirals of the

wires of each pair in aligned relation and offset laterally with respect to each other; said wires having their ends permanently connected together and each wire of each connected pair being in interconnected relation on opposite sides 5 of the same with the wires of two different adjacent connected pairs of wires.

4. A wire fabric composed of helically coiled wires having their ends connected together and arranged in unit pairs, with the spirals of the 10 wires of each pair in aligned relation and offset laterally with respect to each other; each wire of each connected pair being in interconnected relation on opposite sides of the same with the wires of two different adjacent unit pairs of wires. 15

5. A wire fabric composed of helically coiled wires arranged in pairs and each pair having their ends rigidly connected with the spirals of the 20 wires of each pair in aligned relation and offset with respect to each other and lying in the same plane, with one spiral of said first pair passing through adjacent spirals of wires of adjacent connected pairs of wires on both sides of the same, and the other spiral of the first pair passing through adjacent spirals of connected 25 pairs of wires on both sides of the same which differ from the connected pairs whose wires are engaged by the first-named spiral.

6. A wire fabric composed of helically coiled wires having their ends connected together and 30 arranged in unit pairs, with the spirals of the wires of each unit pair in aligned relation and offset with respect to each other and lying in the same plane, with a spiral of the first-named pair passing through adjacent spirals of other 35 unit pairs of connected wires on opposite sides of the first-named spiral with the second spiral of the first-named pair passing through the adjacent spirals of other unit pairs of connected wires on opposite sides of the same; the wires 40 engaged by the second spiral of the first-named pair belonging to pairs of connected wires differing from those with which the first-named spiral is engaged.

7. A wire fabric composed of helically coiled 45 wires arranged in pairs, with the spirals of the wires of each pair in aligned relation and offset with respect to each other and lying in close surface engagement with each other longitudinally and transversely of the fabric; said pairs of wires 50 having their ends permanently connected together and each wire of each pair being in interconnected relation with a wire of different adjacent connected pairs of wires.

8. A wire fabric composed of helically coiled 55 wires having their ends connected together and arranged in unit pairs, with the helices of the wires of each pair in aligned relation and offset with respect to each other and lying in close surface engagement with each other longitudinally 60 and transversely of the fabric; each wire of each connected pair being in interconnected relation with a wire of different adjacent unit pairs of wires.

9. A fabric of helically coiled wires made up of 65 a plurality of sub-fabrics with their spirals in interconnected relation and all in the same plane; the wires of said sub-fabrics lying in nested relation and in close engagement.

10. A fabric of helically coiled wires made up of 70 a plurality of sub-fabrics with their spirals in interconnected relation and all in the same plane; said sub-fabrics lying in nested relation and in close engagement and having wires connected in pairs having offset relation and wherein the in- 75

dividual wires of said pairs form part of different sub-fabrics.

11. A fabric of helically coiled wires comprising a plurality of sub-fabrics made up of interconnected helically coiled wires arranged in connected pairs in offset relation and in the same plane and wherein individual wires of said pairs form part of different sub-fabrics; said wires having a definite relation in groups which are repeated throughout the extent of the fabric.

12. A fabric of helically coiled wires comprising a plurality of sub-fabrics—three in number—and each made up of helically coiled wires in interconnected relation with their ends connected 15 in pairs and lying in the same plane; said sub-fabrics lying in nested relation and in close engagement and wherein the individual wires of said pairs form part of different sub-fabrics; said wires having a definite grouped relation which is 20 repeated throughout the extent of the fabric.

13. A unit element for use in the production of wire fabric comprising a pair of helically coiled wires nested in transversely spaced relation and having their ends permanently connected 25 together to maintain such spaced relation.

14. A unit element for use in the production of wire fabric comprising a pair of helically coiled wires disposed in nested relation with their helices in transverse alignment with respect to 30 their length and offset with respect to each other and having their ends permanently connected together to maintain their offset spaced relation.

15. The method of making a wire fabric of helically coiled wires which comprises arranging 35 pairs of said wires with their helices in transverse alignment with respect to their length and in offset relation; twisting the separate wires of each pair into engagement with the separate wires of other pairs disposed in the same offset relation, and connecting the ends of said wires 40 in pairs to maintain their helices in the offset aligned relation with respect to each other and the wires of adjacent pairs.

16. The method of making a wire fabric of 45 helically coiled wires which comprises arranging said wires in pairs in the same plane with their helices in transverse alignment with respect to their length and in offset relation; twisting said wires into engagement with the separate 50 wires of other pairs disposed in the same offset relation; the separate wires of each pair interconnected with the separate wires of different pairs of adjacent wires, and connecting the ends of said wires in pairs to maintain their helices 55 in the offset aligned relation with respect to each other and the wires of adjacent pairs.

17. The method of making a wire fabric of 60 helically coiled wires which comprises arranging pairs of said wires with their helices in transverse alignment with respect to their length and in offset relation; twisting the separate wires of

each pair in engagement with the separate wires of other pairs disposed in the same offset relation, the helices of the respective wires lying in close surface engagement with each other longitudinally and transversely of the fabric, and connecting the ends of said wires in pairs to maintain their helices in the offset aligned relation with respect to each other and the wires of adjacent connected pairs.

18. The method of making a wire fabric of helically coiled wires which comprises arranging said wires in pairs in the same plane with their helices in transverse alignment with respect to their length and in offset relation; twisting the separate wires of each pair in engagement with the separate wires of adjacent pairs on each side of the first pair, the respective wires of each pair engaging with separate wires of different adjacent pairs and the helices of the respective wires lying in close surface engagement with each other longitudinally and transversely of the fabric, and connecting the ends of said wires in pairs to maintain their helices in the offset aligned relation with respect to each other and the wires of adjacent connected pairs.

19. The method of making a wire fabric of helically coiled wires disposed in grouped relation which comprises arranging pairs of said wires with their helices in transverse alignment with respect to their length and in offset relation; twisting the separate wires of each pair into engagement with the separate wires of other pairs disposed in the same offset relation to form a plurality of groups which are repeated throughout the extent of the fabric, and connecting the ends of said wires in pairs to maintain their helices in the offset aligned relation with respect to each other and the wires of adjacent pairs; the relation of the wires being such that a plurality of sub-fabrics is produced which together 40 form a fabric with closely engaging helices.

20. The method of making a wire fabric of helically coiled wires disposed in grouped relation which comprises arranging said wires in pairs in the same plane with their helices in transverse alignment with respect to their length and in offset relation; twisting said wires into engagement with the separate wires of other pairs disposed in the same offset relation to form a plurality of groups which are repeated throughout the extent of the fabric, the separate wires of each pair interconnecting with the separate wires of different pairs of adjacent wires, and connecting the ends of said pairs of wires to maintain their helices in the offset aligned relation with respect to each other and the wires of adjacent pairs; the relation of the wires being such that a plurality of sub-fabrics is produced which together 55 form a fabric with closely engaging helices.

OTTO CARL SCHERFEL.
